COPPER MATTING FURNACE AND METHOD OF CONSUMING FUEL THEREIN.

FILED FEB. 3, 1919.

Inventor,
H. H. Stout

by *Lacy & Lacy, Atty.*

UNITED STATES PATENT OFFICE.

HARRY HOWARD STOUT, OF DOUGLAS, ARIZONA, ASSIGNOR OF FIFTY-FIVE PER CENT TO PHELPS DODGE CORPORATION, A CORPORATION OF NEW YORK.

COPPER-MATTING FURNACE AND METHOD OF CONSUMING FUEL THEREIN.

Application filed February 3, 1919. Serial No. 274,829.

To all whom it may concern:

Be it known that I, HARRY HOWARD STOUT, a citizen of the United States, residing at Douglas, in the county of Cochise and State 5 of Arizona, have invented certain new and useful Improvements in Copper-Mattting Furnaces and Methods of Consuming Fuel Therein, of which the following is a specification.

10 This invention relates to improvements in copper matting furnaces and methods of consuming fuel therein.

I have discovered in the operation of reverberatory furnaces, in the production of 15 copper ore that the rated or actual capacity of such a furnace is far below its maximum or possible capacity. This deficiency in output, I attribute to the very principles upon which the construction of reverberatory fur-

20 naces is based, namely, the continual dropping of the arch of the furnace from the firing end to the skimming end. As is well known, the arch is dropped in this manner in order to obtain a reverberation of the flame

25 and its deflection toward and over the ore upon the floor of the furnace, the generally accepted presumption having heretofore been that the heat is transferred to the ore by convection rather than by radiation. I

30 have made the discovery through careful investigation, that the principles upon which the reverberatory furnace is constructed are erroneous and that the most effective method of transferring the heat is by radiation.

35 Therefore one of the important objects of the present invention is to provide a copper matting furnace wholly distinct in its characteristic features of construction from the usually employed reverberatory furnace and

40 in which the transfer of heat by radiation, and by radiation alone, is assured, the furnace of the present invention being therefore designed upon principles diametrically opposed to those upon which the reverbera-

45 tory furnace is constructed. That I am warranted in making this radical departure from the heretofore generally accepted principles involved in the construction and operation of furnaces of this general type, is evi-

50 denced by the fact that in carrying out my invention I am enabled to increase and in fact multiply the output of such a furnace without, however, increasing the hearth area thereof.

55 The amount of fuel which can be consumed

in a given period of time in a matting furnace of this general type is the controlling factor in establishing the capacity or output of the furnace; the more fuel it is possible to consume in such a furnace, the greater 60 will be the output of the furnace. In the reverberatory furnace, because of the dropping of the arch from the firing end to the skimming end which is considered essential in such a furnace, it is not possible to pass 65 sufficient air through the furnace to support the combustion of a maximum quantity of fuel. The very nature of the furnace inhibits free and unrestricted passage of air therethrough and therefore the quantity of 70 fuel which can be consumed is limited. In other words, in the reverberatory type of furnace the gas outlet is restricted, and as this is one of the disadvantages presented by this type of furnace, it is an object of the 75 present invention to provide a copper matting furnace having an enlarged gas outlet so that the passage of air through the furnace is unrestricted thus enabling me to consume in the furnace a maximum quantity of 80 fuel. In fact, my method of consuming fuel in a copper matting furnace constructed in accordance with my invention, involves the principle of utilizing the entire transverse combustion-sustaining area of the furnace 85 for this purpose, and in this respect my invention differs radically from the reverberatory type of furnace in which, in fact, in addition to the restriction of the passage of air through the furnace, combustion is ef- 90 fected only in a more or less horizontal zone immediately above the slag line, thus utilizing only a relatively small portion of the transverse combustion-sustaining area of 95 the furnace.

As before stated, one of the objects which I have in view is to provide for the consumption of a maximum quantity of fuel in any given period of time so as to proportionately increase the capacity or output of the furnace, and in addition I employ in my furnace at the firing end a plurality of rows of burners as distinguished from the single row of burners ordinarily employed in the reverberatory type of furnace and located im- 100 mediately above the slag line.

In consideration of the foregoing it will be seen that my invention embraces two salient features, namely, first the provision of a copper matting furnace devoid of the 110

dropping arch, which is the distinguishing feature of the reverberatory furnace, and having an enlarged gas outlet; and second the utilization of a plurality of rows of 5 burners as distinguished from the single row ordinarily employed in the reverberatory type of furnace.

In the accompanying drawings:

Figure 1 is a vertical longitudinal sectional view through a copper matting furnace constructed in accordance with the principles of the present invention and in which the method of consuming fuel contemplated by the present invention may be 10 followed out;

Fig. 2 is a vertical transverse sectional view through the furnace looking in the direction of the firing end;

Fig. 3 is a similar view looking in the 20 direction of the skimming end.

It is to be understood that the accompanying drawings are not intended to disclose a construction which must be strictly adhered to in utilizing the principles of the present 25 invention, but that the views of the drawings are intended only to illustrate in a general way an example of a furnace embodying the principles of the invention and in which the method of the invention may 30 be practiced.

In the drawings, the arch of the furnace is indicated by the numeral 1, the floor of the furnace by the numeral 2, the firing end of the furnace by the numeral 3, and the gas 35 outlet in the skimming end of the furnace by the numeral 4. The approximate slag line is indicated by the numeral 5.

In the general oblong form of its floor or 40 hearth, the furnace of the present invention does not differ materially from the ordinary reverberatory furnace, and as the length and breadth of the hearths or reverberatory furnaces and, consequently, their 45 hearth areas vary, so with my type of furnace the hearth dimensions may likewise vary although the elongated form thereof is retained.

One of the distinguishing features of my 50 furnace, however, resides in the fact that the arch 1 extends horizontally throughout substantially its entire length. It is true that this arch from a point near the firing end of the furnace is slightly inclined upwardly in the direction of the said end but this is done solely to decrease deterioration 55 of the arch due to the licking of the flames against this portion thereof. The fact remains that, as stated above, the arch is horizontal throughout substantially its entire 60 length, and by the term "horizontal" I mean that this arch does not drop continuously from the firing end to the skimming end of the furnace as is invariably the case in the reverberatory type of furnace. In other 65 words, the interior of the furnace is no more

restricted at its skimming end than at its firing end, the arch of the furnace having substantially the same elevation at its skimming end as at its firing end. For example, one furnace which I have designed and 70 which is in operation is approximately 94 feet in length, the arch being about 84 feet in length and extending horizontally throughout this length except for approximately 23 feet at the firing end where it is inclined 75 with a rise of one foot in the 23. As above stated, this slight inclination of the arch near the firing end is provided solely to decrease deterioration of the arch due to the licking of the flames and it is not intended 80 to, nor can it possibly effect any reverberation of the flames, and in fact may be entirely dispensed with if found desirable. The point to be considered is that the distance between the furnace arch at the skimming end and the slag line is equal to or 85 no less than the distance between the said arch and the slag line at a point relatively close to the burners at the firing end of the furnace and that between these two points 90 the said arch extends horizontally and is neither dropped nor inclined. In other words, the transverse combustion-sustaining area of the furnace is uniform substantially through the entire length of the furnace. 95

As before noted, another feature of the invention is the enlargement of the gas outlet 4. Due to the fact that the furnace arch is horizontally disposed throughout its length and the transverse combustion area 100 of the furnace is therefore uniform throughout the length of the furnace, this space is not restricted at the skimming end of the furnace as in the reverberatory type of furnace so that there is unrestricted passage 105 of air through this space and to the gas outlet 4. In stating that this outlet is enlarged, I mean that the same is larger in proportion to the other dimensions of the furnace than would be considered good practice in 110 the designing of a furnace of the reverberatory type. In fact the area of this outlet will be such that the flow of gaseous products of combustion from the furnace will 115 approximate 35 feet per second calculated at the temperature of the gases.

In general, in the reverberatory type of furnace but a single row of fuel burners is provided and this row is located transversely of the firing end of the furnace and at a 120 level immediately above the slag line. That only one row of such burners has been employed in this type of furnaces is probably due to the fact that it has been found impractical to consume more fuel than this 125 single row of burners will supply, in this type of furnace, because of the dropping of the arch and the restricted passage of air through the furnace. Having designed my furnace with a non-dropping arch and en- 130

larged gas outlet, so that there may be a non-restricted passage of air through the furnace, and of the gaseous products of combustion from the furnace, which features 5 combined enable me to utilize the entire transverse combustion-sustaining area of the furnace in supporting the combustion of fuel, I provide means whereby a greatly increased amount of fuel may be supplied 10 for combustion, properly distributed, and thoroughly mixed with the air as it is consumed. In accomplishing this result I employ, instead of the single row of horizontal burners previously employed and located 15 immediately above the slag line, a plurality of such rows as illustrated in the drawings and indicated by the numeral 6, these rows of burners being supplied with fuel, as for example by a manifold 7, or each row of 20 burners may be independently controlled without in any way departing from the invention. In the arrangement illustrated in the drawings, I make use of three rows of 25 burners, one row, which is the lowermost row and which corresponds to the row here- 30 tofore employed in the reverberatory furnace, being located immediately above the slag line, another row which is the uppermost row, being located immediately below the arch 1 of the furnace, and the third row being located substantially midway between the first and second-mentioned rows. Of course, I am at liberty to employ a greater 35 or less number of rows of the burners, and the number of burners in each row may be varied in accordance with the dimensions of the furnace and other conditions. Also, each row may comprise the same number of burners or the number may differ in the various 40 rows. By reason of this arrangement it will be evident that in the operation of the furnace a maximum quantity of fuel will be supplied for combustion, properly distributed, and thoroughly mixed with the air, 45 and that substantially the entire transverse combustion-sustaining area of the furnace will be utilized in supporting the combustion of the fuel, and inasmuch as before 50 stated the capacity of the furnace is increased in ratio to the increase in the amount of fuel which can be consumed therein, it is evident that the capacity or output of a furnace constructed in accordance with my invention and in which fuel is consumed by 55 the method herein described, will be the maximum capacity. For example, the ordinary metallurgical copper matting reverberatory furnace, 18 feet wide and 90 feet long 60 in the ordinary smelting operation has had a daily tonnage capacity of approximately 350 tons. This tonnage has not varied to any great extent in any of the ordinary or normal smelters in operation, and in one of

these furnaces the average capacity per day 65 for a year was 344 tons, with a fuel ratio of 77/100ths of a barrel of oil. With a similarly proportioned furnace but constructed in accordance with the principles of my invention and substantially as illustrated in the 70 drawings, I have succeeded, in carrying out my method, in reaching a daily capacity of 920 tons with a fuel ratio of 66/100ths of a barrel of oil.

In ordinary reverberatory furnace practice, approximately 50 cubic feet of combustion space is required to sustain the combustion of one pound of powdered coal per minute, whereas by my method, in which the entire transverse combustion-sustaining 75 area of the furnace is utilized, I am enabled to burn one pound of powdered coal per minute in 16 cubic feet of combustion-sustaining space as compared with the 50 cubic feet previously required. 80

I wish to again emphasize the fact that while at the firing end of the furnace, the arch is slightly inclined upwardly for a short distance, this inclination cannot possibly result in a reverberation of the flames 85 and is, as stated, provided merely to prevent deterioration of the arch as far as possible due to the licking of the flames. For all intents and purposes the arch of the matting furnace embodying my invention is 90 horizontal throughout its entire length, the slight inclination at the firing end being 95 negligible.

The fact will be appreciated that because of the distribution of the fuel to a large 100 number of burners, the fuel will become more thoroughly mixed with the oxygen of the air as the fuel is consumed and there will, consequently, be a more rapid oxidation of the fuel resulting in a more economical consumption thereof. 105

I have previously pointed out in the description of the furnace that the gas outlet is enlarged, or, in other words, is larger than would be considered good practice in the 110 construction of the ordinary reverberatory furnace, taking into consideration the other dimensions of the furnace, and as an example of the relative size of the gas outlet and the transverse combustion sustaining 115 area of the furnace, such furnaces as have so far been built in accordance with my invention have a transverse combustion sustaining area of approximately eighty-nine square feet and the gas outlet has an area of approximately seventy-seven square feet. 120

Having thus described the invention, what is claimed as new is:

1. The method of consuming fuel in a copper matting furnace which comprises propagating flame over substantially the entire area of the firing end of the furnace between the slag line and arch. 125

2. In a copper matting furnace, means for propagating flame over substantially the entire area of the firing end of the furnace between the slag line and the arch.
- 5 3. In a copper matting furnace, means for propagating a blast of flame longitudinally of the furnace in the direction of the skimming area thereof and throughout substantially the entire transverse combustion sus-
10 taining area of the furnace.
4. A copper matting furnace having a horizontal arch and an escape for the gaseous products of combustion proportioned to deliver the said products at a velocity ap-
15 proaching approximately 35 feet per second.
5. A copper matting furnace having a combustion-sustaining space of substantially uniform dimensions and having an escape for the gaseous products of combustion pro-
20 portioned to deliver the said products at a velocity approaching approximately 35 feet per second at the temperature of the gases.
6. A copper matting furnace provided at its firing end with a bank of burners ex-
25 tending from a point substantially immedi-
ately above the slag line to a point substan-
tially immediately below the arch.
7. A copper matting furnace having a combustion-sustaining space of substantially uniform dimensions, and a plurality of horizontal rows of burners at the firing end of the furnace.
8. A copper matting furnace having a non-dropping arch, and a bank of burners extending substantially from side wall to side wall of the furnace chamber at the firing end thereof.
9. A copper matting furnace having a non-dropping arch, and a bank of burners extending vertically substantially from the slag line of the roof of the furnace chamber at the firing end thereof.
10. A copper matting furnace having a non-dropping arch, and a bank of burners occupying substantially the entire transverse area of the furnace chamber at the firing end thereof.

In testimony whereof I affix my signature.

HARRY HOWARD STOUT. [L.S.]
